UNITED STATES PATENT OFFICE.

FRANK L. FISHER, OF INDIANAPOLIS, INDIANA, ASSIGNOR OF ONE-HALF TO WILLIAM NAY BOGESS, OF DECATUR, ILLINOIS.

PREPAY-BOX FOR TELEPHONES.

1,285,970.

Specification of Letters Patent. Patented Nov. 26, 1918.

Application filed March 22, 1917, Serial No. 156,617. Renewed October 4, 1918. Serial No. 256,917.

To all whom it may concern:

Be it known that I, FRANK L. FISHER, a resident of Indianapolis, county of Marion, and State of Indiana, have invented certain 5 new and useful Improvements in Prepay- Boxes for Telephones, of which the following is a specification.

This invention relates to improvements in telephone systems and particularly to pre- 10 pay boxes, designed for use in automatic systems, that is, systems wherein automatic signaling means at subscribers' stations and selective mechanism is used at a central station, instead of operators. It is designed 15 as an improvement over the invention disclosed and claimed in my pending applica- 20 tion for improvements in telephone systems, filed January 24, 1916, Serial Number 73,955. In the circuit there disclosed, two coils were 25 used to control the disposition of the coin, the operation being dependent upon the condition of the circuits, one coil when energized causing the coin to be deposited in the safe, and the other causing it to be returned 30 to the depositor, in case the connection is not made. This circuit was found to be very satisfactory, but subject to one objection in practice, and that is, that, if the calling party before the called party answers, were 35 to operate the receiver hook quickly, the coin return coil would be energized to return the coin and still the connection would not be broken. This is due to the fact that the connection is controlled by a slow acting relay 40 at the central station.

To obviate this difficulty, I place a slow acting relay across the coin depositing coil for the purpose of opening the circuit to the coin return coil, so that in order to energize 45 the latter, the receiver hook must remain up long enough to allow the said slow acting relay in the box to fall back before the coin return coil will be energized and this will be sufficient to permit the connection controlling slow acting relay at the central station to break the connection.

It is therefore the principal object of this invention to provide a system of this character in which the coils will always be op- 50 erated in the proper manner and the coin handled properly.

To the accomplishment of the foregoing and such other objects as may hereinafter appear, my invention consists in the combina- 55 tion, construction and arrangement of parts

hereinafter described and then sought to be defined in the appended claims, reference being had to the accompanying drawings forming a part hereof, and which show merely for the purpose of illustrative disclosure, a preferred embodiment of my invention, it being understood that various changes may be made in practice within the scope of the claims without digressing from my inventive idea. 60

In the drawings,

Figure 1 represents a view in front elevation of a prepay box constructed according to my invention, the coin being removed and parts broken away to facilitate dis- 70 closure;

Fig. 2 represents a view in elevation of the right hand side of the box showing the coin ways, and the cover being shown in section;

Fig. 3 represents a view in elevation of the 75 left hand side of the box;

Fig. 4 is a diagrammatic illustration of the telephone set and prepay box at a subscriber's station, showing the normal condition of the circuit. 80

I have not illustrated in detail the set at the station, as that is of standard construction used in automatic systems, as at present installed. However, a full showing is made of the coin or prepay box with its contained 85 wiring and mechanism. In addition, in Fig. 4, I show a diagram of the wiring of the set at a station to which reference is made, it being recalled that in automatic systems, lifting the receiver from the hook breaks one 90 contact and makes another, and that signaling impulses are controlled by a selecting mechanism including a dial and various spring contacts. The numerals 1, 2, 3 and 4 designate binding posts or terminals in a 95 telephone instrument itself. 5 designates the receiver, 6 the transmitter, and 7 the receiver hook, making connection alternately with contacts 8 and 9. The selecting mechanism is merely indicated by contacts 10 and 100 11 and 12. The receiver hook 7 is connected to terminal 1 by the conductor *a*. Conductor *b* connects terminal 2 with contact 11. Conductor *c* connects terminal 3 with contact 12. Conductor *d* connects terminal 4 with contact 9 of the receiver hook. Conductor *e* connects contact 8 with the receiver 105 5 and also has conductor *f* connected to contact 10. Conductor *g* connects contact 11 and terminal 2 with the transmitter 6.

The prepay or coin box has a similar series of five terminals or binding posts designated as 0, 1^a, 2^a, 3^a and 4^a, respectively, terminals 1^a, 2^a, 3^a and 4^a being connected 5 with the correspondingly designated terminals 1, 2, 3 and 4 of the set by the conductors 1^b, 2^b, 3^b and 4^b respectively.

To complete the description of the wiring and circuits, I will mention some of the 10 mechanism in the prepay box, still referring particularly to Fig. 4. Mounted therein, are the magnets A and B, condenser C, and slow acting relay D. The magnet A is polarized. Contacts 13, 14 and 15 are also mounted in 15 the box, the latter being a double spring contact, normally in contact with 13, which contact is broken when the contact 13 is raised when spring contact 15 bears against contact 14 to establish a connection.

20 The wiring connections of these parts are as follows: Conductor *h* connects terminal 0 to contact 15 having the branch conductor *i* leading to one side of the condenser C. Conductor *j* connects terminal 1^a to one side 25 of coil B, the other side of which is connected by conductor *k* to the contact 16 of the slow acting relay D. The other contact 17 of relay D is connected by means of conductor *l* to contact 14, *m* indicating part of 30 this connection which leads to one side of the relay D and having the other conductor *n* leading to one side of the coil A, the other side of which is connected by conductor *o* to the other side of relay D. The other side of 35 coil A has the conductor *p* leading to the other side of the condenser C and to terminal 3^a. Conductor *q* connects contact 13 with terminal 2^a. The ringing set E is across contacts 0 and 4^a.

40 The prepay or coin box itself and its contained mechanism are shown in Figs. 1 to 3, inclusive. It has mounted therein the two magnets or coils A and B, the condenser C, the slow acting relay D, and the binding 45 posts or terminals 0, 1^a, 2^a, 3^a and 4^a, previously referred to. These magnets or coils have the single armature 20 pivoted therebetween and have the usual spring controlled members permitting this movement in either 50 direction when the proper magnet is energized and causing the return of the armature to its normal position when the circuit is broken. These magnets or coils are suitably supported on the iron bracket 21, and it 55 is understood that the core of coil B is insulated from this bracket. On the side of the box adjacent the armature I mount the coin run-way 22 which begins at the coin receiving slot and has two termini, one being 60 the return tray 23 and the other the delivery chute 24 into the safe 25. The coin is directed positively into one or the other by means described in my said co-pending application, according to the condition of the circuits.

65 Mounted beneath the magnets or coils A

and B, is the long operating arm 26, this being pivotally mounted and having its coin supporting end portion 28 positioned in the coin run-way so that a coin deposited in the slot will drop thereon and be supported 70 thereby. This lever arm controls the position of contacts 13, 14 and 15, the spring arm 29 carrying the contact 13, this arm being the longest and having the insulating bearing member 30 which is engaged by the end 75 extension 31 of lever 26. The lowest arm 32 is a spring member which forms contact 15 and is adapted to contact with either the upper arm 29 or the intermediate arm 33 which is contact 14. The normal tendency of 80 spring arm 32 is to move upwardly, but as its contact engaging end bears against arm 29, contacts 14 and 15 are held apart until the lever arm 26 is depressed by the weight of a coin thereon, which raises spring arm 29 and 85 permits spring arm 32 to move upwardly to cause contacts 14 and 15 to engage.

The only circuits which need be described in this application, are those relating to the action of the coin controlling coils or magnets. When the receiver at the calling station is removed from its hook and the coin is dropped into the slot, and rests on the end 90 of lever arm 26, contacts 13 and 15 will be separated and 14 and 15 connected, the circuit for the selective impulses being as follows: terminal 1^a, connector 1^b, terminal 1, conductor *a*, hook 7, contact 8, conductor *e*, receiver 5, transmitter 6, conductor *g*, contacts 11 and 12, conductor *c*, terminal 3, connector 3^b, terminal 3^a, conductor *p*, coil or magnet A, conductor *n*, conductor *m*, contacts 14, 15, conductor *h*, line terminal 0. As the slow acting relay D is bridged across coil 95 A, current is also flowing through the relay 100 by means of conductor *o* to conductor *m*, the rest of the circuit being as described. This, therefore, opens the contacts 16 and 17 so that there will be no current flowing through coil B. As coil A is polarized the current is 105 flowing therethrough in the wrong direction so that it is not energized. When the receiver at the called station is removed from its hook, the direction of the current is reversed by means of the usual connector relays at the central station and the magnet 110 A energized so that the armature is moved and the means actuated to cause the coin to drop into the safe.

If the receiver at the calling station is replaced on its hook before the called station answers, this last mentioned circuit is broken and the slow acting relay returns to its normal position. The circuit is then from line terminal 1^a, conductor *j*, coil B, 115 conductor *k*, contacts 16, 17, conductor *l*, conductor *m*, contacts 14, 15, conductor *h*, line terminal 0, so that the coil or magnet B is energized to move the coin so that it will be deposited in the return tray. It will be un- 120 125 130

derstood that this condition does not occur until the slow acting relay returns to its normal position and contacts 16 and 17 are engaged. This, therefore, prevents the party 5 at the calling station from quickly actuating the receiver hook and energizing the coil or magnet B to return the coin without breaking the connection at the central station, this being possible with prior circuits 10 on account of the fact that the slow acting relay is used at the central station for connection purposes.

In case the calling party is on a party line, and does not listen in before depositing the 15 coin, and the line is busy, the current is not sufficient to operate coil or magnet A which is polarized, but will operate the slow acting relay D so that when receiver is replaced, coil or magnet B which is not polarized, will 20 operate to return the coin, this coil or magnet B being operated by current in either direction.

It is to be noted that both coils are never on the line together, and that this circuit 25 gives greater security in that no condition can cause the coils to operate in the wrong manner. It is not necessary to have the coin return coil or magnet polarized. The slow acting relay D is bridged across the coil A.

30 What I claim is:—

1. In a telephone system, the combination of talking and listening instrumentalities, signaling mechanism, a prepay box, means for supporting a coin, electro-magnets for 35 controlling the disposition of the coin to be returned or to be deposited, interconnections controlled by said coin supporting means whereby the talking and listening instrumentalities are placed in series with one of 40 said electro-magnets while a coin is supported thereon, and slow acting means for controlling the circuit through the coin return electro-magnet.

2. In a telephone system, the combination 45 of talking and listening instrumentalities, signaling mechanism, a prepay box, means for supporting a coin, a polarized electro-magnet for causing the coin to be deposited, another electro-magnet for causing the coin 50 to be returned, a slow acting relay bridged across said polarized electro-magnet and having contacts to control the circuit through said coin return electro-magnet and interconnections controlled by said coin supporting means whereby the talking and listening 55 instrumentalities are placed in series with one of said electro-magnets while a coin is supported thereon.

3. In a telephone system, the combination 60 of talking and listening instrumentalities, signaling mechanism, a prepay box, a lever arm for supporting a coin, a polarized electro-magnet for causing the coin to be deposited, another electro-magnet for causing the coin 65 to be returned, a slow acting relay

bridged across said polarized electro-magnet and having contacts to control the circuit through said coin return electro-magnet and interconnections controlled by said lever arm for placing the system in condition for 70 proper operation, depending upon the conditions at the stations.

4. In a telephone system, the combination of talking and listening instrumentalities, signaling mechanism, a prepay box, means 75 for supporting a coin, a polarized electro-magnet for causing the coin to be deposited, another electro-magnet for causing the coin to be returned, and slow acting means for controlling the circuit through said coin return electro-magnet.

5. In a telephone system, the combination of talking and listening instrumentalities, signaling mechanism, a prepay box, means for supporting a coin, a polarized electro- 85 magnet for causing the coin to be deposited, another electro-magnet for causing the coin to be returned, and a slow acting relay adapted to break the circuit through said coin return electro-magnet when energized. 90

6. In a telephone system, the combination of talking and listening instrumentalities, signaling mechanism, a prepay box, means for supporting a coin, a polarized electro-magnet for causing the coin to be deposited, another electro-magnet for causing the coin to be returned, a slow acting relay adapted to break the circuit through said coin return electro-magnet when energized, said relay being in circuit when the receiver hook contact is made, but being out of the circuit when the receiver hook contact is not made. 95

7. In combination, in a telephone system of the character described, electro-magnets for controlling the deposit and return of the 100 coin and a slow acting relay for controlling the circuit through the coin return electro-magnet.

8. In a telephone system, the combination of talking and listening instrumentalities, 110 signaling mechanism, a prepay box, a lever arm pivotally mounted therein and adapted to receive and be depressed by the weight of a coin, a pair of electro-magnets having a common armature pivotally mounted, means 115 connected to said armature for moving the coin in either direction off of said lever arm, a slow acting relay bridged across the coin deposit magnet and arranged to break the circuit through the coin return magnet when 120 energized.

9. In a telephone system, the combination of talking and listening instrumentalities, signaling mechanism, a prepay box, a lever arm pivotally mounted therein and adapted 125 to receive and be depressed by the weight of a coin, a pair of electro-magnets having a common armature pivotally mounted, means connected to said armature for moving the coin in either direction off of said lever arm, 130

a slow acting relay bridged across the coin deposit magnet and arranged to break the circuit through the coin return magnet when energized, the coin deposit electro-magnet being energized when the connection with the called station is established so that the coin is moved to be deposited, the coin re-

turn electro-magnet being energized when the receiver of the calling station is replaced on its hook before the connection is completed with the called station, so as to move the coin for return. 10
